ALEXANDER V. SAHAROFF,

INVENTOR

BY

ATTORNEY

UNITED STATES PATENT OFFICE.

ALEXANDER V. SAHAROFF, OF CINCINNATI, OHIO, ASSIGNOR TO WORTHINGTON PUMP AND MACHINERY CORPORATION, OF NEW YORK, N. Y., A CORPORATION OF VIRGINIA.

INTAKE SILENCER.

Application filed April 21, 1926. Serial No. 103,596.

This invention relates to an intake silencer particularly designed for use on air compressors and analogous mechanisms wherein air or gas is drawn into the cylinder of the machine, preferably by the suction of the machine during operation.

An object of the present invention is to provide a silencer or muffler which will effectively muffle or reduce the noises caused by air or gases entering a chamber or cylinder of a machine, the said silencer including a pulsating chamber into which the air or gas is drawn by the suction operation of the mechanism through an inlet tube of smaller area than the pulsating chamber, which inlet tube has a choked or reduced inlet to allow an uninterrupted flow of air into the tube and from the tube into the pulsating chamber, thereby eliminating the noises contingent with the suction of air or gas into the machine as well as eliminating the noise of the back-puff in the suction.

With these objects in view, the invention consists in various features of construction and combination of parts, which will be first described in connection with the accompanying drawings, showing an intake silencer of the preferred form embodying the invention, and the features forming the invention will be specifically pointed out in the claim.

Figure 1 is a vertical longitudinal section through the improved silencer.

Figure 2 is a vertical cross-section through the silencer taken on the line 2—2 of Figure 1.

Figure 3 is a horizontal section through the silencer taken on the line 3—3 of Figure 1.

Referring more particularly to the drawings, the improved suction or intake muffler includes a casing 1, which is preferably of cylindrical construction, and has one end open as shown at 2. A plug 3 is fitted into the opening 2 and held therein against displacement by a set screw 4. The plug 3 is provided with a threaded bore 5 into which an inlet nipple 6 is threaded. The bore 5 is countersunk and threaded and the inlet end of the inlet-tube 7 is threaded into the threaded countersunk portion 8 of the bore

5. The inlet-tube 7 extends longitudinally in a pulsating chamber 9 formed within the casing 1, and it has its outlet end flattened and extended laterally, as clearly shown in Figures 2 and 3 of the drawing, to provide a relatively thin wide outlet-opening 10 from which the air or gas passes into the pulsating chamber 9. The walls of the inlet tube 7 curve inwardly as they approach the wide, thin outlet-opening 10. It is preferable to make the area of the outlet-opening 10 greater than the area of the inlet bore 11 of the inlet nipple 6 so as to permit air or gas to pass from the tube 7, freely into the pulsating chamber 9 where it is permitted to expand and accumulate. The air or gas is drawn from the pulsating chamber 9 through the outlet-opening 12. The outlet-opening 12 is positioned at one side of the pulsating chamber 9 and at the end of the casing remote from the inlet.

The cross-sectional area of the tube 7 is greater than the cross-sectional area of the inlet bore 11 thereby providing a restricted or choked entrance into the tube 7 and pulsating chamber 9 which allows an interrupted flow of air into the expansion or pulsating chamber 9. By properly proportioning the pulsating or expansion chamber 9, the pressure in the expansion chamber is kept below atmosphere and the back-puff and noise contingent therewith is absorbed in the chamber 9 and muffled and prevented from interfering with the inlet of air through the restricted nozzle opening 11.

It will be understood that the invention is not to be limited to the specific construction or arrangement of parts shown but that these may be modified widely within the invention defined by the claim.

What I claim is:

In an intake silencer, an outer casing forming a pulsation chamber, a tube concentric within said chamber, the said tube having a choked inlet and a single relatively wide, narrow outlet opening into said chamber, the walls of said tube curving inwardly as they approach said outlet.

In testimony whereof I affix my signature.

ALEXANDER V. SAHAROFF.
